TIE FOR EXTENSION TRACKWAYS

Lloyd E. Harvey, Logan, Ohio, assignor of one-half to James H. Keith, Gloucester, Ohio

Application July 19, 1933, Serial No. 681,151

3 Claims. (Cl. 238—10)

This invention relates to improvements in rail ties, and has for a primary object the provision of an improved tie involving adjustable clamping devices by which a rail may be secured in connection with the tie for adjustment lengthwise of a given trackway in a quick and convenient manner and without using the customary threaded bolts and nuts.

In mining, excavating and various other constructional activities, it is necessary to advance wheeled track-mounted machinery over temporary tracks in order to maintain contact of the machinery with a retreating working operation. For instance, in coal mines particularly, a main trackway is laid which leads into a working place or room in which the coal face or seam to be attacked is located. As the coal is loaded out, the working face retreats from the established trackway and in order to produce temporary trackways which can be laid up to the working face, it is at present customary to secure to the advanced terminating ends of the established trackway continuing rail sections cut into various lengths to meet the requirements of the retreating face. It is frequently inconvenient, as well as costly, to provide a working crew with short rail sections of various sizes to meet the rapidly changing track requirements, so that the work of the mine crew is frequently interrupted and their services lost while a suitable temporary track is being laid, although in practice, the temporary trackway need be but less than a score of feet in length.

It is a further important object of the present invention to provide a tie to which the advanced rail sections of a trackway may be securely yet readily connected, with the rails of the advanced or temporary trackway arranged in inverted relationship with respect to the rails of the permanent trackway, and wherein the clamping mechanism of my improved tie structure is such as to securely hold the extension rails in their inverted positions in connection with the permanent rails so that as the work progresses, the said temporary rails may be moved longitudinally along their points of contact with the permanent rails and retained in such adjusted positions, permitting of the advance of machinery thereover, by the improved tie structure. By this means, the temporary rails may be of standard lengths and need not be, as at present, cut into sections of various length, thus providing a considerable saving in rail costs as well as eliminating delays in excavating or mining operations incident to the placing of extension trackways.

With these and other objects in view, which will appear as the description proceeds, the invention consists in the novel features of construction, combination of elements and arrangements of parts hereinafter fully described and 5 pointed out in the appended claims.

In the accompanying drawings:

Fig. 1 is a side elevation of a mine trackway, extending to the working face of a coal seam or the like, and illustrating my improved extension 10 trackway in its operative position;

Fig. 2 is a vertical longitudinal sectional view taken along the trackway and associated ties;

Fig. 3 is a vertical transverse sectional view on the line III—III of Fig. 2; 15

Fig. 4 is a horizontal sectional view on the plane indicated by the line IV—IV of Fig. 3;

Fig. 5 is a perspective view of one of the ties;

Fig. 6 is an enlarged vertical sectional view taken through the tie structure and illustrating 20 its clamping members in engagement with a single rail;

Fig. 7 is a detail perspective view of one of the outside clamping plates;

Fig. 8 is a similar view of the inner clamping 25 plate;

Fig. 9 is an enlarged vertical sectional view taken through the tie structure and illustrating its clamping members in engagement with a single inverted rail; 30

Fig. 10 is a top plan view of the trackway in its operative position.

Referring more particularly to the drawings, the numeral 1 designates the customary permanent trackway of, for example, the type found 35 in coal mines or in other similar operations over which portable track-mounted machinery operates. Such a trackway consists of the customary rails 2, ties 3 and their associated fastening devices 4. Such a permanent trackway can be 40 laid up to the working face only for a certain distance. Usually coal mines employ a crew known as track men whose work it is to advance a trackway, such as indicated at 1, as close as practicable to the working face. However, such 45 a working face recedes. For instance, the coal or other mineral matter is mined by kerfing the seam, disrupting the face by means of explosive, and is then loaded into mine cars as indicated at 5 and removed from the working place. This 50 results in the continued receding of the working face from the permanently laid trackway, and in order to provide for sustained mining operations, it is necessary to lay temporary track means 55 so that coal cutting or mining machinery,

wheeled loading machines or the like may be kept in proper contact and efficient working relationship with such a retreating face.

To avoid the necessity and wasteful practice 5 of cutting standard length rails into short lengths of various sizes to complete such an advanced or emergency trackway, the present invention provides an improved tie which forms the basis for the extension trackway, which latter has been indicated at 6 in Fig. 1 in the drawings. 10 Each tie in the extension trackway comprises in its preferred form an inverted channel bar 7 which is adapted to have its vertical sides 8 arranged to engage directly with the floor of a mine room, although in certain instances, the bar 7 may be secured to the upper surface of a standard wooden tie; normally this is not necessary as the emergency ties are laid directly on the mine floor where the latter is of such 15 quality as to permit this to be done.

Each end of the tie or bar 7 is provided with a plurality of centrally located inner and outer longitudinally extending slots 9 and 10 respectively and slidably positioned on the upper surface 25 face 11 at each end of the tie are inner and outer clamping plates 12 and 13 respectively.

Each of the outer clamping plates 13 comprises a flat horizontal body portion 14 which flatly engages with the upper surface 11 of the tie 7, and fastening devices such as threaded bolts, rivets or the like pass through the outer slots 10 formed in said tie and openings in the body portion 14 to slidably unite the said outer clamping plates in various positions of longitudinal adjustment in connection with the tie. 30 Each of the outer clamping plates terminates in a curved outer edge 15, while the inner portion of each of the plates 13 terminates in an upwardly directed short vertical wall 16 of a height corresponding approximately to that of the base flange of a rail. The wall 16 terminates in an inwardly directed extension 17 which is adapted to engage with the upper surface of the base flange of a rail. The extension 17 does not 35 possess the full width of the base flange on one side of a rail but is materially shorter, and terminates in an upwardly directed wall 18 which possesses a height substantially less than one-half of that of the web of a standard mine rail. 40 The wall 18 then terminates in an inwardly directed horizontally disposed web 19 and the inner edge of the latter terminates in an upwardly directed vertical wall 20, which is adapted to engage with the vertical side wall of a rail web 45 and ends immediately below the ball or head of a standard mine rail.

Each of the inner plates 12 comprises a flat horizontally disposed body portion 21 which is provided centrally with a plurality of openings 60 arranged to register with the slots 9 in the tie channel 7, and through which fastening devices such as threaded bolts or nuts, or in certain instances rivets, pass and slidably and adjustably unite the inner clamping plates to the tie 7.

The outer end of the body portion 21 of each plate 12 terminates in an arcuately curved edge 22, while the inner portion of each of the plates 12 terminates in an upwardly directed vertical wall 23, of a height corresponding to that of the outer edge of the base flange of a standard mine rail. The wall 23 terminates in an inwardly directed integral extension 24, which overlies and firmly engages with the upper surface of the outer edge of the base flange of a rail, and the extension 24 terminates, in turn, in an upwardly 65

directed wall 25 which is of lesser height than the corresponding wall 18 of the outer plates and is of such height as to be equivalent to that of the ball of a rail when the latter is inverted. The wall 25 terminates in an inwardly directed 5 web 26 arranged in a substantially horizontal plane below that of the web 19, and the web 26 terminates in an upwardly directed vertical wall 27 which is adapted to engage with the web 10 of a rail.

To maintain these clamping plates in association with either a single or double rail arrangement, the arcuate edges 15 and 22 of the plates 12 and 13 are arranged for engagement with the curved edges formed on the ends of a pair of 15 bars 28, which are pivoted as at 29 in connection with the upper surfaces of the ties 7. These pivoted bars serve to advance the plates 12 and 13 into firm frictional engagement with the side 20 surfaces of the rails 2 and 6 to hold the latter 20 in proper positions of gage for the advancement of rolling stock thereover.

As shown in the drawings, the rails 6 of the extension trackway are arranged in inverted relationship with respect to the rails 2 of the permanent trackway. That is, the rails 6 are disposed on the outer sides of the rails 2 with their base flanges resting on the upper surfaces of the heads of the rails 2, and with the heads of the rails 6 substantially in contact with the base 30 flanges of the permanent rails. When the rails are thus assembled, the plates 12 and 13 are separated their maximum distance with the shorter ends of the bars 28 in contact with the arcuate outer edges of said plates. When the inverted rail sections 6 are to be advanced, the outer clamps 13 are loosened and the rails moved forward the desired distance, the portions of the rails 2 which had previously been engaged by the overlapping ends of the sections 6 will be 40 resting on the ties 7 alone and they must be supported by the plates 12 and 13. To accomplish this, the outer plates 13 are moved toward the rails 2 until they press against the outer surfaces thereof. They are then secured in place by the 45 nuts and bolts and locked in this position by turning the longer sides of the bars 28 into place against the outer ends of the plates 13. The extended rail 6 is then secured by retightening the clamps 13 and the addition of more ties and 50 clamps if necessary. When this occurs, the ties 7 may be elevated slightly to contact with the head of the inverted rail, and the inner plates 12 are adjusted to directly engage with the webs 55 of such inverted rails and are held in such engagement by revolving the inner bars 28 so that their longer ends will engage with the arcuate edges 22. By this longitudinal adjustment of the clamping plates, the latter are retained in desired engagement with the rail sides so as to 60 preserve the gage of both the permanent and extension trackway and this is accomplished in a single, compact structure wherein separable parts, which are apt to become lost or misplaced, are avoided. The trackway may be readily laid up to the working face and the extension rails moved longitudinally at will to conform to the face as the latter retreats. The construction of the ties is simple, rugged, inexpensive and is not likely 65 to become out of order. Particularly, the tie avoids the use of short different length rail sections in the formation of the extension trackway, and enables mining or other similar operations to be carried on in a sustained manner with- 70 75

out the usual delays incident to trackway developments.

What is claimed is:

1. Rail holding means for extension trackways comprising a bar, inner and outer clamps mounted upon each end of said bar, each of said clamps being formed to provide an elongated body mounted on the upper surface of said bar, said body terminating in a rail-engaging head having a shoulder for abutment with the longitudinal edge of the base flange of a rail seated in a normal upright position on said bar, said head being additionally provided with a vertical flange disposed to directly engage the inner surface of a vertical web of a rail and an intermediate shoulder disposed between said first-named shoulder and said flange, said intermediate shoulder being shaped to receive the head of a rail disposed in an inverted position with the ball thereof in engagement with said bar, and means for securing said clamps in holding engagement with rails mounted on said bar.

2. Rail holding means for extension trackways comprising a metallic tie, spaced inner and outer clamps positioned upon the upper surface of said tie and relatively adjustable longitudinally of said tie to hold between the adjoining surfaces of said clamps rails in the following positions: (1) a rail with its base flange resting on the upper surface of said tie, (2) a pair of rails, one with its base flange resting on the upper surface of said tie and the other in an inverted position with one of its

base flanges engaging with the ball of the upright rail and with the ball of the inverted rail in engagement with one of the base flanges of the upright rail and (3) a rail in an inverted position alone, each of said clamps comprising an elongated body formed to engage with the upper surface of said tie and terminate at its forward end in a head, said head being provided with three shouldered offsets, the first of said offsets engaging with the base flange of a rail disposed in a normal upright position on the tie, the second of said offsets being shaped to engage with the ball of an inverted rail and the third of said offsets with the web of a rail disposed in an upright or inverted position on said tie, and threaded means for maintaining the relatively adjusted positions of said clamps on said tie and in holding engagement with associated rails.

3. A rail holding clamp for extension trackways comprising a flat elongated tie engaging body, and a rail engaging head integrally formed with said body and disposed at one end thereof, said head being provided with three shouldered offsets disposed in different horizontal levels, the first of said offsets being formed for engagement with the outer edge of the base flange of a rail, the second of said offsets being formed to receive the ball of an inverted rail and the third or highest of said offsets being shaped to engage the side of the web of a rail arranged in either upright or inverted positions.

LLOYD E. HARVEY.
